Atkins

UNITED STATES PATENT OFFICE.

NOEL CARRICO, OF SIDNEY, MONTANA, ASSIGNOR OF ONE-HALF TO FRANK C. HUGHES, OF EVANSTON, ILLINOIS.

METHOD OF MENDING ELECTRIC RESISTANCE ELEMENTS.

1,399,420.

Specification of Letters Patent.

Patented Dec. 6, 1921.

Application filed September 11, 1920. Serial No. 409,660.

To all whom it may concern:

Be it known that I, NOEL CARRICO, a citizen of the United States, residing at Sidney, in the county of Richland and State of 5 Montana, have invented a new and useful Improvement in Methods of Mending Electric Resistance Elements, of which the following is a specification.

This invention relates to improvements in 10 mending electric resistance elements and applies more particularly to those resistance elements, commonly used for heating in electric heaters, toasters and the like, which are most frequently made of a wire (usually an 15 alloy of nickel and chromium) formed into a helix or spiral with convolutions.

It is well known that such an element sometimes becomes broken from misuse or unusual strains, or burns out at a weak or 20 thin point, before the usefulness of the element as a whole has expired. By the use of my invention an element so broken can be quickly, easily and cheaply mended so as to restore its former usefulness, thus greatly 25 prolonging its life.

The invention is illustrated in the drawing of which Figure 1 shows a resistance element in place in its mounting with the finished repair, Fig. 2 is a plan view of the 30 broken element before repair, Fig. 3 shows the first steps in the making of the repair, Fig. 4 shows the application of the flux, Fig. 5 is a section on the line 5 of Fig. 2, and Fig. 6 is an enlarged section of the wires 35 at the point of repair.

In the practice of my invention, the broken ends 7 and 8 of the resistance element are overlapped and the convolutions of the helix interlocked or interlaced (Fig. 3). I 40 prefer to interlock two or three convolutions of each end, although more or only one may be used. No particular manner of interlocking or interlacing the ends is required, as long as they are sufficiently hooked together 45 to prevent separation. In overlapping the ends, the stretching of the elements will cause the convolutions of which they are formed to act as springs and give a slight tension thus assisting in holding together 50 the interlocked ends. After the broken ends have been thus interlocked, I cover them

with powdered borax 9 (Fig. 4). I prefer to use partially dehydrated borax as it is more adherent, and by its use excessive 55 intumescence is avoided during the rest of

the process. Although I have stated that I use borax, it is obvious that, without detracting from the spirit of my invention, other substances may be used instead. For example, any alkali similar to borax or any suitable flux may be used. After the application of the borax to cover the interlocking of the broken ends, the normal operating current customarily used through the resistance element is turned on, whereupon the broken ends will become united.

At times the quantity of current flowing through the repair may be somewhat increased by short-circuiting some of the coils. However, by the use of my invention the element while in place in the mounting may be quickly repaired using the normal current, *i. e.*, that reaching the device through its regular leads and without making any special connection. This is highly important particularly with heavy translators like domestic ranges which can be restored to usefulness without removing the element as has been heretofore required.

Although I have described certain embodiments of my invention it is to be understood that it is capable of many variations and modifications; and it must, therefore, not be limited except as in the appended claims, in which it is my intention to claim all 85 novelty inherent in my invention, not disclosed in the prior art.

What I claim as new, and desire to secure by Letters Patent is:

1. The method of mending a helical wire 90 electric resistance element by hooking together the broken ends and passing through the element the normal operating electric current.

2. The method of mending a helical wire 95 electric resistance element by hooking together the broken ends, applying a flux and passing through the element the normal operating electric current.

3. The method of mending a helical wire 100 electric resistance element by hooking the end convolution at one of the broken ends with the end convolution at the other broken end, applying a flux and passing through the element the normal operating electric 105 current.

4. The method of mending a helical wire 110 electric resistance element by interlocking a plurality of convolutions at one of the broken ends with a plurality of convolutions

at the other broken end, applying a flux and passing through the element the normal operating electric current.

5. The method of mending a helical wire electric resistance element by overlapping and contacting the broken ends, applying a flux and passing through the element the normal operating electric current.

6. The method of mending a helical wire electric resistance element by overlapping and interlocking the broken ends, applying a flux and passing through the element the normal operating electric current.

7. The method of mending a helical wire electric resistance element by extending the convolutions at the broken ends to overlap the same, contacting the same, applying a flux and passing through the element the normal operating electric current.

8. The method of mending a helical wire electric resistance element by extending the convolutions at the broken ends to overlap the same, hooking the end convolution at one of the broken ends with the end convolution

25 at the other broken end, applying a flux and passing through the element the normal operating electric current.

9. The method of mending a helical wire electric resistance element by extending the convolutions at the broken ends to overlap the same, interlocking a plurality of convolutions at one of the broken ends with a plurality of convolutions at the other broken end, applying a flux and passing through the element the normal operating electric current.

10. The method of mending a helical wire electric resistance element by extending the convolutions at the broken ends to overlap the same, interlocking the ends, applying a flux and passing through the element the normal operating electric current.

11. The method of mending a helical wire electric resistance element by extending the convolutions to put a tension on the same,

overlapping the broken ends, interlocking the two end convolutions, applying a flux and passing through the element the normal operating electric current.

12. The method of mending a helical wire electric resistance element by extending the convolutions to put a tension on the same, overlapping the broken ends, interlocking a plurality of convolutions at one of the ends with a plurality of convolutions at the other end, applying a flux and passing through the element the normal operating electric current.

13. The method of mending a helical wire electric resistance element by extending the convolutions to put a tension on the same, overlapping and interlocking the broken ends, applying a flux and passing through the element the normal operating electric current.

14. The method of joining two parts of a helical wire electric resistance element by stretching the same to put a tension on them, overlapping and interlocking the ends, applying a flux and passing through the two parts the operating electric current normally used with the element.

15. The method of mending an electric resistance element in place in its mounting by bringing the broken ends in contact and passing through the element the current which normally operates the translator of which the element is a part.

16. The method of mending an electric resistance element in place in its mounting by bringing the broken ends in contact, applying a flux to the point of contact, and passing through the element the current which normally operates the translator of which the element is a part.

In testimony whereof, I have hereunto set my hand and seal this 31st day of August, A. D. 1920.

NOEL CARRICO. [L. S.]
